UNITED STATES PATENT OFFICE.

HENRY B. GORMAN, OF LYNCHBURG, VIRGINIA, ASSIGNOR TO UNITED SHOE MACHINERY CORPORATION, OF PATERSON, NEW JERSEY, A CORPORATION OF NEW JERSEY.

SHOE AND METHOD OF MANUFACTURING THE SAME.

Application filed January 4, 1926. Serial No. 79,118.

This invention relates to shoes and the manufacture thereof and is illustrated herein with reference to the attachment of wood heels to shoes although in various aspects its 5 utility is not so limited.

Wood heels are often of considerable height, two inches or more being common, and the stresses to which they are subjected during wear are correspondingly great. In the 10 case of Louis heels particularly the small waists of the heels seriously limit both the number and the length of the attaching nails which can be used. Louis heels, moreover, are commonly formed with an overhanging 15 or projecting breast portion adjacent to their attaching surface, this portion being so thin that no attaching nails can be driven into it. This still further limits the use of attaching 20 nails. As a result of these different limitations, the attachment of wood heels, and particularly wooden Louis heels, to shoes is often much less secure than it should be.

It is, accordingly, an object of the present 25 invention to provide an improved method of securing heels to shoes. As illustrated, my improved method is characterized by the formation of a pair of tabs from the substance of the sole adjacent to the heel-breast line, these tabs being secured to the breast 30 surface of the heel with their outer edges in alinement with the breast corners of the heel. In the case of shoes having, for example, wooden Louis heels these tabs may be completely covered and concealed by a flap, split 35 from the sole of the shoe, such as is commonly used to cover the breasts of Louis heels. These tabs are preferably formed by transversely inclined cuts extending approximately parallel to the edges of the sole, thereby permitting 40 the tabs to be swung inwardly or outwardly (toward each other or apart) so as to bring their outer edges into line with the breast corners of the heel, even though they do not naturally tend to take such positions. If 45 the ends of such tabs are beveled before the heel-breast covering flap is cemented into place, their surfaces will merge with the breast surface of the heel so that after the breast covering is in place, the flaps will not 50 be noticeable in the finished shoe, except as they may serve to give a pleasing plumpness and roundness to the breast portion of the heel.

In another aspect the invention comprises

a shoe having a heel attached thereto with a 55 pair of tabs formed from the sole of the shoe overlying the breast portion of the heel and with the outer edges of the tabs in alinement with the breast corners of the heel. Such tabs act as buttresses and serve materially to assist 60 in a secure attachment of the heel to the shoe.

With the above and other objects and features in view the invention will now be described in connection with the accompanying 65 drawings and pointed out in the claims.

In the drawings:

Fig. 1 is a perspective view of the rear portion of a shoe after the performance of the heel-seat fitting operation but before the attachment of a heel to the shoe, the sole of the shoe being formed with a pair of tabs in accordance with the method of the present invention;

Fig. 2 is a perspective view of the same 75 shoe with a Louis heel attached thereto and with the overhanging or projecting portion of the breast of the heel overlaid by the tabs;

Fig. 3 is a perspective view of the same 80 shoe with the tabs swung so as to bring their outer edges into alinement with the breast corners of the heel, the tabs being secured to the heel breast in that position;

Fig. 4 is a perspective view of the same shoe 85 after the ends of the tabs have been beveled; and

Fig. 5 is the finished shoe with the breast of the heel covered by the usual flap split from the sole.

In practicing the method of the present 90 invention as illustrated herein the heel-seat fitting operation is performed in any usual or suitable manner, except that the surplus stock is not removed from a portion of the heel-seat extending rearwardly about one-half an 95 inch more or less from the heel-breast line. From this portion of the stock is formed a pair of tabs 8, 8, the inner edges of these tabs being formed by cuts 10 (Fig. 1) approximately parallel to the edge of the sole but inclined transversely and extending from a point half an inch or so to the rear of the heel-breast line forwardly to the heel-breast line. The surplus stock to the rear of these tabs is removed in the usual manner, leaving a 100 convex heel-seat 11 corresponding to the concave or cupped attaching surface of the wood heel. In the illustrated shoe a flap 12 has 105

been split from the sole, to be used to cover the breast of the heel in the usual way. Also the shank portion of the sole has been thinned almost to a feather edge, at 13, as is common in the manufacture of women's shoes of light weight.

After the heel-seat fitting operation has been done and tabs 8 have been formed as just related, a wood heel 14 illustrated as of the 10 well-known Louis type and provided with a forwardly projecting, overhanging breast portion 16 is attached to the shoe in any approved manner, for example by gluing and nailing, with its overhanging breast portion 16 positioned beneath the tabs 8, as shown in Fig. 2. Next tabs 8 are cemented or otherwise secured to the breast surface 18 of the heel, the tabs being swung inwardly or outwardly as may be necessary to bring their 20 outer edges 20 into alignment with the breast corners of the heel. This is illustrated in Fig. 3, the taper of the heel being such that it has been necessary to swing tabs 8 inwardly a short distance from the position shown in 25 Fig. 2. In order to cause the surfaces of the tabs to merge in the breast surface of the heel, the ends of the tabs should be beveled. This is illustrated at 22 in Fig. 4, as the next step 30 of the method though it should be understood that the position in the sequence of operations at which the beveling is performed is not of major importance. After the beveled flaps have been secured to the heel-breast the 35 heel-breast covering 12 is cemented into position, as illustrated in Fig. 5, thus completely concealing the tabs in the finished shoe.

Having described the invention, what I claim as new and desire to secure by Letters Patent of the United States is:

40 1. A shoe having a heel provided with an overhanging breast portion, the sole of the shoe being formed with a pair of tabs secured to the overhanging breast portion of the heel with their outer edges in line with the breast corners of the heel, said tabs having beveled ends and inner edges so that their outer surfaces merge in the breast surface of the heel, the tabs and the breast of the heel being covered by a flap split from the sole.

50 2. A shoe having a heel provided with an overhanging breast portion, the sole of the shoe being formed with a pair of tabs secured to the overhanging breast portion of the heel and serving to strengthen the attachment of the heel to the shoe, said tabs having beveled ends and inner edges so that their outer surfaces merge in the breast surface of the heel and being located with their outer edges in alignment with the breast corners of the heel.

60 3. That improvement in methods of manufacturing shoes which comprises forming upon a sole a pair of tabs extending from the heel-breast line of the sole rearwardly and having beveled inner edges, attaching to a 65 shoe to which said sole has been attached a

heel having an overhanging breast portion with said overhanging portion beneath the tabs, and securing the tabs to the overhanging breast portion of the heel with their outer edges in alignment with the breast corners of 70 the heel.

4. That improvement in methods of manufacturing shoes which comprises forming a pair of tabs upon a sole the margins of the shank portion of which are reduced to a 75 feather edge, said tabs being formed by a pair of cuts extending from the heel-breast line rearwardly, said cuts being approximately parallel to the edges of the sole and inclined transversely so that the inner edges of the tabs 80 are beveled, attaching to a shoe to which said sole has been attached a heel having an overhanging breast portion with the overhanging breast portion beneath said tabs, swinging the tabs to bring their outer edges into alignment 85 with the breast corners of the heel, beveling the ends of the tabs, securing the tabs to the breast surface of the heel, and covering the tabs and the breast of the heel with a flap split from the sole. 90

5. That improvement in methods of manufacturing shoes which comprises forming at the heel-breast line of a sole a pair of tabs having beveled inner edges, attaching to a 95 shoe to which said sole has been attached a heel having an overhanging breast portion with the overhanging breast portion beneath said tabs, bringing the outer edges of the tabs into alignment with the breast corners of the heel, and securing the tabs to the breast surface of the heel with their outer edges in line 100 with the breast corners of the heel. 100

6. That improvement in methods of manufacturing shoes which comprises forming a pair of tabs upon a sole by a pair of cuts extending from the rear of the heel-breast line forwardly to the heel-breast line, said cuts being inclined transversely so that the inner edges of the tabs are beveled, attaching to a shoe to which said sole has been attached a 110 heel having an overhanging breast portion with the overhanging breast portion beneath said tabs, and securing the tabs to the breast surface of the heel with their outer edges in alignment with the breast corners of the heel. 115

7. That improvement in methods of manufacturing shoes which comprises forming a pair of tabs approximately at the heel breast line of a sole by a pair of cuts extending substantially parallel to the edges of the sole, attaching a heel to a shoe to which said sole has been attached, swinging the tabs as may be necessary to bring their outer edges into line with the breast corners of the heel, and securing the tabs in place as thus adjusted. 120

8. That improvement in methods of manufacturing shoes which comprises splitting the rear portion of a sole to form a heel breast covering flap extending from the heel end of the sole somewhat forwardly of the heel 130

breast line, forming at the heel breast line of the sole a pair of tabs having beveled inner edges, attaching a heel having an overhanging breast portion to a shoe having a sole so prepared with the overhanging breast portion of the heel beneath said tabs, securing the tabs to the breast surface of the heel with their outer edges in line with the outer corners of said heel, the ends of the tabs being beveled at any desired time during the performance of the operation.

5 prepared with the overhanging breast portion of the heel beneath said tabs, securing the tabs to the breast surface of the heel with their outer edges in line with the breast corners of the heel, and securing the heel breast flap to the breast of the heel thereby also covering the tabs, the ends of the tabs being beveled prior to the covering of the heel breast with the breast flap.

9. That improvement in methods of manu- 15 facturing shoes which comprises forming at the heel breast line of a sole a pair of tabs having beveled inner edges, attaching a heel having an overhanging breast portion to a shoe having a sole so prepared with the overhang- 20 ing breast portion of the heel beneath said

tabs, securing the tabs to the breast surface of the heel with their outer edges in line with the outer corners of said heel, the ends of the tabs being beveled at any desired time during the performance of the operation.

25

10. That improvement in methods of manu- 30 facturing shoes characterized by forming upon a sole a pair of tabs extending from the heel breast line of the sole rearwardly and having beveled inner edges, attaching a heel having an overhanging breast portion to a shoe having such a sole with the overhanging breast portion of the heel beneath the tabs, and beveling the ends of the tabs to cause their surfaces to merge with the breast surface 35 of the heel.

In testimony whereof I have signed my name to this specification.

HENRY B. GORMAN.
